CLAIM

The ornamental design for a high capacity banded battery case for a mobile device, as shown and described.

DESCRIPTION

FIG. 1 is a front elevational view of a high capacity banded battery case for a mobile device with the bottom portion connected;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front and top perspective view thereof;

FIG. 8 is a front and bottom perspective view thereof;

FIG. 9 is a rear perspective view thereof;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a front and top perspective view thereof;

FIG. 17 is a front and bottom perspective view thereof; FIG. 18 is a rear and bottom perspective view thereof;

FIG. 19 is a front elevational view thereof with the bottom portion disconnected;

FIG. 20 is a rear elevational view thereof;

FIG. 21 is a left side elevational view thereof;

FIG. 22 is a right side elevational view thereof;

FIG. 23 is a top plan view thereof;

FIG. 24 is a bottom plan view thereof;

FIG. 25 is a front and top perspective view thereof;

FIG. 26 is a front and bottom perspective view thereof; and, FIG. 27 is a rear and bottom perspective view thereof.

The broken lines in the figures are for the purpose of illustrating environment and form no part of the claimed design.
